DESIGN FOR A LAPEL EMBLEM BUTTON OR THE LIKE

Henry A. Wiley, Washington, D. C., assignor to the Government of the United States

Application May 15, 1942, Serial No. 106,904

Term of patent 14 years

To all whom it may concern:

Be it known that I, Henry A. Wiley, a citizen of the United States, residing at Washington, District of Columbia, have invented a new, original and ornamental Design for a Lapel Emblem Button or the like, of which the following is a specification, reference being had to the accompanying drawing, forming part thereof.

Fig. 1 is a plan view of a lapel emblem button or the like, showing my new design, and

Fig. 2 is an edge elevational view of the same.

The essential features of my design reside in the portion shown in full lines.

While I have shown my design embodied in the form of a button, it is understood that the same may be embodied in other similar articles without departing from the scope of my invention.

I claim:

The ornamental design for a lapel emblem button or the like, as shown and described.

HENRY A. WILEY.
